FIG. 1 is a perspective view of a lens panel showing my new design, the ceiling being shown in broken lines for illustrative purposes only;

FIG. 2 is an enlarged, fragmentary perspective view thereof;

FIG. 3 is an enlarged, fragmentary bottom plan view thereof;

FIG. 4 is an inverted enlarged fragmentary side elevational view thereof.

FIGS. 2, 3 and 4 are fragmentarily shown for convenience of illustration. The lens panel is shaded to show contrast between the transparent lens and the opaque large and small ribs. It is understood that the lens panel may extend indefinitely lengthwise and widthwise.

I claim:

The ornamental design for a lens panel, as shown and described.
